UNITED STATES PATENT OFFICE.

HARRY SHOEMAKER, OF JERSEY CITY, NEW JERSEY.

TRANSMITTING APPARATUS.

No. 926,900.

Specification of Letters Patent.

Patented July 6, 1909.

Application filed December 10, 1908. Serial No. 466,744

To all whom it may concern:

Be it known that I, HARRY SHOEMAKER, a citizen of the United States, residing at Jersey City, in the county of Hudson and 5 State of New Jersey, have invented a new and useful Transmitting Apparatus, of which the following is a specification.

My invention relates to the control of substantial amounts of electrical energy, preferably in a signaling system and preferably by 10 a telegraph key, whereby the key is required to control only a fraction of the entire energy used in representing a signal or message.

It is the object of my invention to control 15 electrical energy in substantial quantities, particularly when in the alternating form, as used in the transmitting apparatus of a wireless telegraph or other system, where the amount of energy to be controlled is relatively 20 great, and yet to be controlled by a key through which only a small fraction of the entire energy passes to represent dots and dashes or other characters. To this end, I provide 25 pairs of differentially related inductances, an inductance of one pair being always in circuit, while the other inductance of that pair is connected in series with an inductance of another pair, the other inductance of the second pair being controlled by the key. 30 And this arrangement of inductances may be carried out to as great a number of pairs as desired.

My invention resides also in other features hereinafter pointed out and claimed.

35 For an illustration of some of the forms my invention may take, reference is to be had to the accompanying drawing, in which:

Figure 1 is a diagrammatic view of a wireless telegraph transmitter involving my invention, in this case showing only two pairs of inductances. Fig. 2 is a diagrammatic view illustrating an arrangement in which a greater number of pairs of controlling inductances is provided. Fig. 3 illustrates a 45 closed magnetic circuit for the inductances. Fig. 4 illustrates the cores of two pairs of inductances, all mounted within a container.

Referring to Fig. 1, G is a source or generator of electrical energy, preferably fluctuating or alternating current energy. Connected in circuit with the source G is a primary P of a step-up transformer and an adjustable inductance or resistance I , and also the inductance L' , the inductances L' and L being

serially connected with each other and in parallel with inductance L^1 . By the closure of the operator's key k , the inductance L^1 is thrown into circuit and in parallel with the inductance L^2 .

The inductances L^1 and L^2 are disposed upon the core C, and are differentially wound or connected and are preferably similar in resistance and ampere turns. And, similarly, the inductances L^3 and L^4 are disposed in relation to the core C' , are differentially wound or connected, and are preferably similar in resistance and ampere turns.

The secondary S, of the transformer T, is bridged by the condensers K and K', and these by a spark gap s and the adjustable inductance I.

A is the aerial conductor, of any suitable form, of a wireless telegraph transmitting station, between which and the earth connection E is connected a variable portion of the inductance I.

The inductance L^1 is always in circuit with the generator G and the primary P. And the inductances L^2 and L^3 are also always in circuit, being connected in series with each other and in parallel with the inductance L^1 . When the key k is depressed current will also flow through the inductive winding or inductance L^1 , but since these coils are in differential relation with respect to each other, and if they are substantially similar in magnetizing effects, the magnetizing effect upon the core C' becomes practically zero and the value of the combined self-induction of the inductances L^3 and L^4 is reduced to practically zero, and, in consequence, a very much greater current will flow through the inductance L^2 . Thus, greater current passing through L^2 then serves, with the current through L^1 in opposition, to render the magnetization of the core C practically zero causing still greater current to flow. And the key k causes a reduction of the inductance to practically zero in the case of the pair L^3 , L^4 , and with this consequent greater current through L^3 the current through L^2 is in consequence greater and suffices; since they are differentially connected, to overcome the magnetizing effect upon the core C, thus again reducing the inductance to practically zero as regards the pair L^3 , L^4 . So it is that the key k need control a current which is a small fraction of the entire current which

90

105

will, in consequence, flow through the primary P and thus supply a relatively great amount of energy to the oscillation circuit including the condensers K , K' and the inductance I . While it is preferred to have the pairs L^1 and L^2 , and L^3 and L^4 similar in resistance, inductance, number of turns, etc., it is to be understood that they may be dissimilar in these regards though the greater effect will be produced when they are so similar. And while there is current passing through the primary P even when the key k is open yet such amount of current is small and may, indeed, be so small as to be incapable of causing sparking at s . For example, a current of 25 amperes through inductance L^4 when the key k is closed, and a like current of 25 amperes through L^3 nets a current of 50 amperes through the inductance L^2 , and with a current of 50 amperes through L^1 nets a current of 100 amperes through the primary P . In such case, the key k is required to handle or control only a quarter of the current. When the key k is open no current passes through L^4 and the inductances L^1 and L^3 being in series permit a very small amount of current to pass and the inductance L^1 also chokes back the current allowing only a very small current to pass. Indeed, in the case above given with the key k open, the current through the primary P was approximately only 5 amperes, but this can be made even smaller by giving the windings or inductances L^1 , L^2 , etc., a greater number of turns or greater inductance.

In Fig. 2 the parts are the same as shown in Fig. 1, except that three pairs of inductances are shown. The pairs L^1 , L^2 with core C , and L^3 and L^4 with core C' are the same as shown in Fig. 1. But instead of having the inductance L^4 connected through the key k , it connects permanently through the inductance L^5 of the third pair and when the key k is closed, through the inductance L^6 also, the pair L^5 , L^6 being disposed upon the core C' . Here again the action is the same as in the case of Fig. 1. The closure of the key k causes the differential pair L^5 , L^6 to become practically non-inductive; this causes, then, the pair L^3 and L^4 to become practically non-inductive; and, in turn, the pair L^1 and L^2 becomes practically non-inductive so that there will flow a very much greater current through the primary P . For example, with the key k closed I have found that a current of 25 amperes will flow through both L^5 and L^6 ; a current of 50 amperes through both L^3 and L^4 ; and a current of 100 amperes through both L^1 and L^2 , thus netting a current of 200 amperes through the primary P . Here it is seen that the key k is required to handle or control only one-eighth of the entire current.

65 While the cores C may take any suitable

form, they are preferably laminated, and in the case where the pairs of inductances with their cores are to be inclosed in a case in close proximity to each other, as is often required in practice, the cores C , C' and C'' 70 of both Figs. 1 and 2 are preferably of the closed magnetic circuit type, as shown in Fig. 3, where the coil L^1 is wound on one limb and the coil L^2 on another. It is to be understood, however, that they may be wound 75 on the same limb or disposed in any other way.

In Fig. 4 a casing or container M is shown in cross section with the cores C , C' , shown in end elevation supported or secured 80 within the casing M . By thus using closed magnetic circuit cores, the inductances being brought in close proximity to each other, will not influence each other except in an inappreciable degree. 85

What I claim is:

1. In transmitting apparatus, the combination with a source of energy, of a plurality of pairs of differentially related inductances associated with said source, an inductance of each pair connected in series with each other, an inductance of a pair connected in parallel with said serially connected inductances, and a transmitter for controlling an inductance of a pair. 95

2. In transmitting apparatus, the combination with a source of energy, of a plurality of pairs of differentially related inductances associated with said source, an inductance of each pair connected in series 100 with each other, an inductance of a pair connected in parallel with said serially connected inductances, and a transmitter for controlling an inductance associated in a pair with one of said serially connected inductances. 105

3. In transmitting apparatus, the combination with a source of energy, of a plurality of pairs of differentially related inductances associated with said source, an inductance of a pair being connected in series with an inductance of another pair, and a transmitter for controlling an inductance in parallel with said inductance of another pair. 110

4. In transmitting apparatus, the combination with a source of energy, of a plurality of pairs of differentially related inductances associated with said source, and a transmitter for controlling an inductance 115 of a pair, whereby the combined inductance of that pair is greatly reduced and the consequent increased current greatly reduces the combined inductance of another pair. 120

5. In transmitting apparatus, the combination with a source of energy, of a plurality of pairs of differentially related inductances associated with said source, an inductance of one pair connected in series with an inductance of another pair, and a transmitter 125 130

for controlling an inductance of a pair, whereby the combined inductance of that pair is greatly reduced and the consequent increased current greatly reduces the combined inductance of another pair.

6. In transmitting apparatus, the combination with a source of energy, of a plurality of pairs of differentially related inductances associated with said source, an inductance of each pair having a terminal in common with an inductance of every other pair, and a transmitter for controlling the second inductance of a pair.

7. In transmitting apparatus, the combination with a source of energy, of a plurality of pairs of differentially related inductances associated with said source, an inductance of one pair connected in series with an inductance of another pair, the second inductance of another pair connected in series with an inductance of the third pair, and a transmitter for controlling an inductance of a pair.

8. In transmitting apparatus, the combination with a source of energy, of a plurality of pairs of differentially related inductances associated with said source, an inductance of each pair having a common terminal, an inductance of each pair connected at its uncommon terminal through the inductance of another pair, and a transmitter for controlling an inductance of a pair.

9. In transmitting apparatus, the combination with a source of energy, of a plurality of pairs of differentially related inductances associated therewith, a closed magnetic circuit for each pair of inductances, the pairs of inductances with their closed magnetic circuits being placed in proximity to each

other, and a transmitter for controlling an inductance of a pair.

10. In transmitting apparatus, the combination with a source of energy, of a plurality of pairs of differentially related inductances associated therewith, a closed magnetic circuit for each pair of inductances, the pairs of inductances with their closed magnetic circuits being placed in proximity to each other, a casing inclosing said pairs of inductances, and a key for bringing into circuit an inductance of a pair.

11. In transmitting apparatus, the combination with a source of energy, of a plurality of pairs of differentially related inductances associated therewith, a pair of inductances having a closed magnetic circuit, said pair of inductances with its closed magnetic circuit being disposed in proximity to another pair of inductances, and a key for bringing into circuit an inductance of a pair.

12. In transmitting apparatus, the combination with a source of current, of a plurality of pairs of differentially related inductances associated therewith, a transmitter for controlling an inductance of a pair, the arrangement of said pairs with respect to each other being such that the increased current resulting from the reduction of the combined inductance of a pair shall operate to reduce the combined inductance of another pair to further increase the total current.

In testimony whereof I have hereunto affixed my signature in the presence of the two subscribing witnesses.

HARRY SHOEMAKER.
